G. A. DOSTAL

LABEL AFFIXING APPARATUS

Filed March 14, 1921

By His Attorneys ^{George W. Dorem}
Emery Farney Blair & Bogart

Patented May 19, 1925.

UNITED STATES PATENT OFFICE.

GEORGE A. DOSTAL, OF NEW YORK, N. Y., ASSIGNOR TO PICTORIAL SOAP MANUFACTURING CORPORATION, OF NEW YORK, N. Y., A CORPORATION OF NEW YORK.

LABEL-AFFIXING APPARATUS.

Application filed March 14, 1921. Serial No. 452,148.

To all whom it may concern:

Be it known that I, GEORGE A. DOSTAL, a citizen of the United States, and resident of the borough of Manhattan, city and State of New York, have invented certain new and useful Improvements in Label-Affixing Apparatus, of which the following is a specification.

This invention relates to apparatus for affixing labels, and especially to apparatus for affixing labels to cakes of soap in connection with a process by which the labels are affixed to one face of the soap cakes and that face is protected against wearing away by a coating of paraffin in such manner that the labels remain permanently attached to the soap during use.

In accordance with the said process the soap cake is provided with a coating of paraffin upon one face, the paraffin being applied in melted condition. While the paraffin is still soft and tacky the label is applied to the coated face of the soap cake, the paraffin serving as an adhesive to secure the label. When the label is applied to the hot paraffin there is a tendency for the label to wrinkle and for bubbles to be entrapped between the label and the soap thus giving an unsightly appearance to the soap cake.

The present invention has for an object to provide improved apparatus for smoothing out the wrinkles and bubbles so that the labels will lie flat and smooth against the soap cake.

The invention will be fully described hereinafter and the features of novelty will be pointed out in the appended claims.

In the accompanying drawings which illustrate an example of the invention without defining its limits, Fig. 1 is a plan view of the apparatus; Fig. 2 is a side elevation thereof and Fig. 3 is a detail section on the line 3-3 of Fig. 1.

The apparatus illustrated in the drawing and which will be described for the purpose of illustration forms a part of a machine which automatically applies paraffin to one face of a soap cake, affixes a label to said face and applies more paraffin over the label to protect the same. Said machine comprises parallel ways, conveyor means for moving soap cakes along said ways, tanks of hot paraffin beneath the ways and wicks in said tanks of hot paraffin be-

neath the ways and wicks in said tanks arranged to be engaged by the soap cakes to apply paraffin thereto as the soap cakes pass along the ways, together with a label-affixing mechanism arranged to apply a label to each soap cake while the paraffin is soft and tacky. Another part of such machine is described in my companion application for Letters Patent for apparatus for applying paraffin to soap cakes filed concurrently herewith Serial No. 452,149. From the label-applying mechanism the soap cakes pass to the smoothing mechanism hereinafter described and which is designed to smooth out the previously applied labels. This mechanism comprises a slideway, conveying means for moving soap cakes along the slideway and a smoothing roll which is arranged to press the labels flat against the soap as it is moved along the slideway by the conveying means.

The slideway is formed by two parallel supporting angle bars 5 which are so spaced that they engage the soap cakes only adjacent their side edges, and which, if desired, may be made adjustable toward and from each other to accommodate soap cakes of different widths.

The smoothing mechanism is shown as comprising a smoothing roll 6 arranged to engage the label face of each soap cake as it passes along the slideway. Conveniently this roll may be so positioned as to engage the underside of the soap cake which is so turned that the label face is presented downward to the roll 6. A weighted pressure roll 7, or its equivalent, is preferably provided to press the soap cakes against the roll 6 to insure satisfactory operation. The pressure roll in the illustrated example is rotatably supported on arms 8 pivoted to permit free movement toward and from the smoothing roll; adjustable stop screws 9 are preferably provided for limiting the downward movement of the arms 8 and pressure roll 7 carried thereby and for adjusting the position of said pressure roll 7 relatively to the roll 6. The smoothing roll 6 is preferably heated so that if the paraffin between the label and the soap cake has hardened it will be sufficiently heated and softened by the roll 6 to permit the label to be readily ironed smooth. It is also desirable to provide a coating of paraffin between the roll 6 and the label to serve as a lubricant during

the smoothing operation and to provide a protective coat over the label.

The pressure roll 7 may be idle but preferably is driven in a direction and at a speed corresponding to the travel of the soap cakes through the machine. The smoothing roll 6 may be driven at any desired speed and in either direction. I prefer to so drive this roll that it will have substantially the same surface speed as the soap cake so that the action of the roll will be a pressing action rather than a rubbing action. There is thus little or no tendency for the roller to displace the label upon the soap cake.

As shown the smoothing roll shaft 10 may be positively driven by a sprocket 11 and sprocket chain 12 from a suitable source of power as for example the main power shaft of the machine. The pressure roll shaft 14 may be driven through suitable gearing so arranged as to drive the roll in the desired direction and so arranged as not to interfere with the vertical movement of the roll as the roll moves to accommodate soap cakes of different thicknesses. As shown a sprocket gearing is provided comprising the sprocket chains 15, 16 a pair of intermeshing gears 17, 18 and sprocket wheels connected with the gears and with the shafts 10 and 14 respectively.

The heating of the smoothing roll 6 and the provision of a coat of paraffin may be accomplished as shown by arranging a tank 19 of hot paraffin in contact with which the roll 6 rotates. The heat of the paraffin is transmitted to the roll and a coat of paraffin sufficient for the intended purpose is picked up by the roll during its rotation.

The soap cakes are moved along the slide-way by conveyor belts 20 mounted on suitable pulleys 21, 22 and arranged in co-operating pairs and spaced from each other in the direction of feed as shown in Fig. 1. These belts are arranged to engage only the side edges of the cakes and therefore do not rub against the labels, and because of the spaced arrangement do not engage a soap cake at the time it is being operated upon by the smoothing means.

This provision facilitates the arrangement of the rolls 6 and 7 by providing a free space where the rolls may be located without interference with the belts. Guides 23, 24 are provided along the slideway to bridge the gaps between contiguous conveyor belts 20. These guides and the ways are recessed to avoid interference with the smoothing and pressure rolls 6 and 7 as indicated at 25 and 26 in Fig. 2.

The conveyor belts 20 are driven by any suitable means as for example by means of horizontal shafts 27 extending above and parallel to the slideway and operatively connected with vertical shafts 28 by means of bevel gears 29, the vertical shafts 28 carry-

ing the pulleys 21 over which the conveyor belts 20 travel.

The horizontal shafts 27 may be operatively connected with a cross shaft 30 by bevel gears 31 to be driven in unison from a suitable source as for example from a main power shaft of the machine.

In the operation of the apparatus the cakes of soap are carried forward by the conveyor belts 20 and pass over and rub against a wick 32 standing in a tank 33 of melted paraffin, each cake being pushed beyond the gaps between contiguous pairs of conveyor belts 20 by successive cakes which remain in contact with the last previous pair of belts. In order to prevent deviation of the cakes from the intended path guides 37, similar to the guides 23 and 24, may be provided between the belts 20 at the point where the wick 32 is located. It will be noted that the arrangement is such that during the time a soap cake is in engagement with the wick 32 it is not engaged by the belts 20. As many coats of paraffin as desired may be applied by passing the soap cakes over successive wicks. In the apparatus illustrated the paraffin in the tanks is heated as for example by electric resistance coils 34, 35, it being understood that any other suitable type of heating device may be substituted if desired.

An overflow connection 36 may be provided from the tank 33 to the tank 19 which is on a lower level, and at the same time suitable provision may be made for constantly introducing a fresh supply of hot paraffin to the upper tank. After passing over the wick 32 the cakes of soap are picked up by the belts 20 located beyond said wick in the direction of feed, and are carried along thereby and finally are caused to pass between the rolls 6 and 7. The latter roll serves to maintain the soap cakes in proper contact with the smoothing roll 6 which flattens out the label and by its action eradicates any bubbles, wrinkles or other defects which may have developed during or after the application of said label. At the same time at least a portion of the paraffin carried by the roll 6 is transferred to the label in the form of a protecting coat covering the same. The result of this is a perfectly smooth label covered with paraffin and free from any blemishes resulting from the application of said label to the cake. After the soap cakes leave the smoothing device an additional coating of paraffin may be applied to still further cover and protect the face of the label.

It is to be understood that the embodiment shown is illustrative only and that variations in the construction illustrated may be made within the scope of the claims without departing from the spirit of the invention.

I claim:

1. In an apparatus of the character described, in combination, laterally engaging conveying means for moving forward successively soap cakes having labels applied to the center portions of one face thereof, ways supporting said soap cakes adjacent their side edges without contacting with the center face portions to which the labels are applied, and a smoothing device arranged to press against the labeled face of each cake as it travels past said device substantially as and for the purpose described.
2. In an apparatus of the character described, in combination, feeding means for moving forward successively soap cakes having labels applied to one face thereof, a rotatable smoothing roll arranged to bear against the labeled face of each soap cake as it passes said roll and press the label smooth against the soap cake, a weighted roll yieldably mounted above the smoothing roll, means for limiting the downward movement of the weighted roll, means for driving the two rolls while permitting vertical movement of the weighted roll and means for heating and lubricating said smoothing roll substantially as and for the purpose described.
3. In apparatus of the character described in combination, spaced parallel ways arranged to support, adjacent their side edges, soap cakes bearing centrally positioned labels free of contact with the ways,

conveyor means for moving the soap cakes along said ways, an ironing roll over which said soap cakes pass, a weighted roll mounted for vertical movement above the ironing roll and arranged to yieldably hold the soap cake down against the ironing roll, a tank arranged to hold paraffin in contact with said ironing roll, means for heating the paraffin to maintain it and the roll in heated condition whereby the labels are ironed smooth against the soap cakes and a coating of paraffin is applied by said ironing roll.

4. The method of smoothing labels affixed to soap cakes by paraffin which consists in ironing the labels by means of a heated lubricated rotating roll substantially as described.

5. The method of affixing labels to soap cakes which comprises applying thin coats of hot paraffin successively to the soap cake while the soap cake is in relatively cold condition, subjecting such successive coats to radiant heat during the interval of time between the application of a coat and the next succeeding coat whereby each coat is cooled from the interior while having its outer face maintained relatively soft, applying a label after the last coat while still in tacky condition and applying a further coat of paraffin thereover.

In testimony whereof I have hereunto set my hand.

GEORGE A. DOSTAL.
